(57) **CLAIM**

The ornamental design for a clip for sweat absorbing pad as shown and described.

DESCRIPTION

FIG. 1 is a front perspective view of a clip for sweat absorbing pad showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a front perspective view thereof, shown in an environment of use.

The broken lines in the drawings depict environment and form no part of the claimed design.

1 Claim, 9 Drawing Sheets
